BUTTONHOLE SEWING MACHINE

Edward P. Spaine and Harold C. Faulkner,
Bridgeport, Conn., assignors to The Singer
Manufacturing Company, Elizabeth, N. J., a
corporation of New Jersey

Application May 16, 1942, Serial No. 443,236

17 Claims. (Cl. 112—71)

This invention relates to sewing machines, more particularly of the buttonhole type, which are adapted to sew a buttonhole having radially disposed stitches at one end, which may be an eyelet-end, and a bar at the other end. The bar may be produced by the sewing machine which effects the production of the buttonhole or by a separate barring machine in a subsequent operation.

The primary object of the present invention is to provide novel means automatically operable during the production of the radially disposed stitches to vary the relative feed between the needle and the work to provide for making a greater or less number of stitches at the eye-end of the buttonhole.

A further object of the invention is to provide means, conveniently and quickly operable, for increasing the spacing between successive stitches in a buttonhole throughout the entire length of the buttonhole.

A still further object of the invention is the provision with a buttonhole sewing machine having a first feeding mechanism for effecting relative shifting between the needle and the work, thereby to space the stitches to form a buttonhole, of a novel second feeding mechanism automatically operable for overfeeding the first feeding mechanism and effective to more widely space the stitches at predetermined portions of the buttonhole.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 is a left side elevational view of a buttonhole sewing machine, embodying the invention.

Fig. 2 is a bottom plan view of the machine.

Fig. 3 represents an enlarged vertical sectional view taken through the machine-standard, showing the connections for actuating the clutch of the improvement.

Fig. 4 represents a vertical sectional view taken substantially along the line 4—4, Fig. 3.

Fig. 5 represents a sectional view taken substantially along the line 5—5, Fig. 4, illustrating the details of the clutch in the improvement.

Fig. 6 represents a sectional view taken substantially along the line 6—6, Fig. 4.

Fig. 7 is a face view of the clutch shown in

Figs. 5 and 6, illustrating the relative position of the declutching levers and the clutch-rollers, with the release-cam superposed in its proper position to show its preferred shape.

5 Fig. 8 is a sectional view taken along the line 8—8, Fig. 7.

Fig. 9 is a sectional view, similar to Fig. 4, but showing the parts in position such that the clutch is in operative position throughout the entire stitching cycle.

10 Fig. 10 represents a vertical sectional view taken substantially along the line 10—10, Fig. 1.

Fig. 11 represents a horizontal sectional view taken substantially along the line 11—11, Fig. 10.

15 Fig. 12 is a diagrammatic view of a buttonhole as produced on the conventional eyelet-end buttonhole sewing machine.

Fig. 13 is a view similar to Fig. 12, showing a buttonhole produced on a sewing machine fitted with the present invention.

20 Fig. 14 is a view of a buttonhole produced by a buttonhole sewing machine equipped with the present invention adjusted for operation throughout the entire buttonhole-producing cycle.

25 Fig. 14a is a view of a "lapel buttonhole" produced on a machine fitted with the present improvement.

30 Fig. 15 represents a horizontal sectional view taken substantially along the line 15—15, Fig. 1.

Fig. 16 represents a horizontal sectional view taken substantially along the line 16—16, Fig. 1.

35 Fig. 17 is a face view of the plate used for indicating the position of adjustment of the pivotal axis of the actuating lever for either eyelet-end buttonholes or straight buttonholes.

Fig. 18 is a fragmentary bottom plan view of the usual feed-cam, showing its two driving gears and the toothed clutch for connecting one of the gears to the feed-cam.

40 Fig. 19 represents a sectional view taken substantially along the line 19—19, Fig. 18.

In the preferred embodiment of the invention illustrated, the machine-frame comprises a hollow box-like bed 1 from one end of which rises the standard 2 of an overhanging bracket-arm 3 terminating in a head 4.

The stitch-forming mechanism is of the well known type embodying an upper endwise reciprocating and laterally vibratory needle 5 and under thread mechanism constructed substantially in accordance with the disclosure of U. S. Patent No. 1,372,473, dated March 22, 1921, and comprising a turret 6, Fig. 1, which is turnable about a vertical axis and carries threaded and nonthreaded loopers and a pair of loop-detainers.

(not shown). The needle-actuating mechanism is also mounted to turn about a vertical axis coincident with the axis of the turret 6 and the usual turning movements are imparted to the upper needle and under looper mechanisms by the connected upper and lower sector gears 7 and 8, respectively, which are actuated in unison by the usual connections with the cam-groove 9, Fig. 2, in the feed-cam 10. This well known mechanism is more completely shown, for example, in U. S. Patents No. 1,162,207, November 30, 1915; No. 15,324, reissued April 4, 1922; and No. 1,534,017, April 21, 1925. The mechanism operates to rotate the stitch-forming devices in one direction during the sewing around the eyelet-end of a button hole and to reversely rotate the stitch-forming devices between sewing periods to restore them to initial position.

The work to be buttonholed is held through the entire buttonhole operation in a work-clamp, indicated as 11, which is of the traveling type. The work-clamp is first rapidly moved over the bed 1 to carry the work forwardly from initial or buttonhole-cutting position to stitching position, then more slowly moved in step-by-step fashion to place the stitches about the buttonhole, and then rapidly returned to initial position. The lower portions, or clamp-plates, of the work-clamp 11 are carried by a cross-slide plate 12, Fig. 2, which, in turn, is carried by a longitudinal slide-frame 13 to which traveling movements are imparted by a link-connection 14, Fig. 2, with a feed-lever 15 having a follower 16 tracking a feed cam-groove in the feed-cam 10. The cross-slide plate 12 is shifted by a lever 17 having the usual connections with the feed-cam 10 and removable pattern-cam 18, the latter of which is secured on the exposed end of a cross-shaft 19 connected by bevel gears 20 and 21, Fig. 3, to the feed-cam 10, so as to run with the latter. For a more complete disclosure of the above described mechanism reference may be had to the U. S. reissued Patent No. 15,324, April 4, 1922.

The rapid feed of the work-clamp from button-hole-cutting position to sewing position and return is effected through the use of the following mechanism: Journaled in the bed 1 is a constantly running rapid feed drive-shaft 22 geared at one end to a main-shaft 23 rotated by means of belt-driven pulley 24 adapted to operate through a conventional form of clutch and stop-motion device S. Mounted on the rapid feed drive-shaft 22 is a worm 25 in mesh with a gear 26 mounted on the cross-shaft 19. Secured to the gear 26 is the live element 27 of a clutch within which is located a driven element fast upon the cross-shaft 19, which driven element includes a plurality of clutch-dog-operating levers having tails 29. When the tails 29 are expanded by a cone 30, slideable on the cross-shaft 19, the clutch is released and the cross-shaft is disconnected from the rapid-feed drive shaft 22. When the cone 30 is withdrawn from the tails 29 of the clutch-dog-operating levers, the clutch is engaged and the shaft 19 is coupled to its drive shaft 22 or, in other words, the rapid-feed is thrown in. This rapid-feed mechanism is constructed substantially in accordance with the disclosure of said U. S. Patent Reissue No. 15,324.

The cone 30 is shifted axially of the cross-shaft 19, to engage and disengage the clutch, by means of an arm 31, forked at its free end to embrace the grooved hub 32 of the cone 30. The other end of the arm 31 is clamped upon a cross-slide rod 33 journaled in the bed 1 and biased by

a coil-spring 34 in a direction to throw out the rapid-feed. The cross-slide rod 33 is shoved endwise against the pressure of the spring 34, to throw in the rapid-feed, by the continuously reciprocating push-bar 35 which is pivoted to one arm of a bell-crank 36, the other arm of which is forked and engages a crank 37 on the rapid-feed drive-shaft 22, Fig. 2. The bell-crank 36 is continuously oscillated about its fulcrum-stud 38 by the crank 37, thus imparting continuous endwise movements to the push-bar 35. The endwise movements of the push-bar 35 are utilized at predetermined times in the stitching cycle to withdraw the cone 30 from the rapid-feed clutch 15 and thereby effect the coupling of the cross-shaft 19 to the drive shaft 22. The throw-out of the rapid feed is accomplished by the coil-spring 34 which functions to shift the cone toward the rapid-feed clutch and thereby uncouple the cross-shaft 19 from the drive shaft 22. Suitable latches and trips (not shown), controlled by the pattern-cam 18 and the continuously running belt-pulley 29, Fig. 2, operate to render operative or inoperative the mechanism for shifting the cone 30. At the completion of the stitching operation, the usual stop-motion lever in its movement to stop the main-shaft 23, operates to release a suitable latch permitting the coil-spring 34 to shift the cone 30 toward the rapid-feed clutch to uncouple the cross-shaft 19 from the drive-shaft 22. It will be understood that the above described rapid-feed is active only during the portions of the cycle immediately preceding and following the sewing period and operates to rapidly shift the work-clamp to and away from sewing position. The rapid-feed mechanism is of well known construction and is substantially the same as that disclosed in the said Reissue Patent No. 15,324 and the U. S. patent to E. P. Spaine, No. 2,165,016, 40 July 4, 1939.

During the portion of the cycle when the stitch-forming mechanism is active, the feed-wheel 10 is driven in a slow step-by-step fashion from the main-shaft 23 through the gears 40, Figs. 1 and 2, 45 from the pin-and-star wheel device 41 which is driven by the main-shaft 23 in the usual manner through the bevel gears 42 and vertical shaft 43 from which the upper or needle-actuating shaft 44 is driven. As fully described in the Reissue Patent No. 15,324, and shown in Figs. 18 and 19 of the accompanying drawings, turning impulses are imparted to the feed-cam 10 by one of the gears 48 which is in mesh with a ring-gear 45 sustained for turning movement in a peripheral notch 46, Fig. 18, provided in the under face of the feed-cam 10. The ring-gear 45 is held in the notch 46 by a plurality of retainers 47, Fig. 19, secured to the peripheral face of the bevel gear 21 integral with the feed-cam 10. Turning impulses imparted to the ring-gear 45 by the meshing gear 40 are transmitted to the feed-cam 10 by one of a plurality of pawls 48 pivoted, as at 49, to the under face of the feed-cam 10 and spring-biased into engagement with ratchet-teeth 50 formed in the inner face of the ring-gear 45. When the stitch-forming mechanism is in operation the ring-gear 45 drives the feed-cam through the one-way acting ratchet-and-pawl connection above described.

The sequential operation of the rapid-feed mechanism and the slow step-by-step feed mechanism in prior machines of the type disclosed in the said Reissue Patent No. 15,324 is as follows: Upon depressing the starting lever of the machine, the constantly running belt-pulley 29,

through suitable connections, operates to lower the work-clamp 11 into work-clamping position and subsequently withdraw the clutch-cone 30 to render the clutch 27 effective to couple the constantly running rapid-feed drive-shaft 22 to the cross-shaft 19 and rapidly rotate the feed-cam 10. Upon reaching stitching position, the clutch-cone 30 is shifted into clutch-releasing position to throw out the rapid-feed mechanism and, simultaneously, the belt-driven pulley 24 is clutched to rotate the main-shaft 23 which drives the feed-cam 10 step-by-step fashion and operates the stitching mechanism. At the completion of the stitching operation the slow step-by-step feed is terminated by the declutching of the belt-driven pulley 24 from the main-shaft 23 and the stopping of the main-shaft in a predetermined stop-position by the stop-motion device S. Simultaneously with the stopping of the slow step-by-step feed, the clutch-cone 30 is withdrawn from the tails 29 of the clutch-dog-operating levers to thereby throw in the rapid-feed mechanism which operates to quickly return the completely stitched buttonhole to buttonhole-cutting position. In "cut-after" machines this buttonhole-cutting operation is effected after the stitching cycle is completed, while in "cut-first" machines the buttonhole-cutting operation is effected before the stitching cycle begins.

The stitch-forming mechanism of the present machine is rotated about a vertical axis to form an eye at one end of the buttonhole. In prior machines the spacing between the successive radial stitches about the eye of the buttonhole has been such that upon reducing the size of the eye, as for example, from the size shown in Fig. 12 to the sizes shown in Figs. 13 and 14a, without reducing the total number of stitches in the complete buttonhole, the stitches are crowded together, resulting in a bulky eye. The present invention relates to novel means by which the spacing of the stitches around the eye of the buttonhole is controlled. To this end the machine is provided with a third feeding mechanism which, in effect, overdrives the slow step-by-step stitching feed, while the stitches are being formed around the eye of the buttonhole, and imparts to the feed-cam 10 step-by-step turning impulses of greater amplitude than those imparted to the feed-cam by the slow stitching feed.

The novel third feeding mechanism consists essentially of a train of connections including a clutch, the effective action of which is automatically controlled, whereby the feeding mechanism is thrown in and out of action at predetermined times in the cycle. Referring to Figs. 4, 5 and 6, the bevel gear 20 has attached to its inner face, preferably by screws 51, a cup-shaped member 52 providing an outer cylindrical clutch-surface 53 substantially concentric with the longitudinal axis of the cross-shaft 19. Disposed within the cup-shaped member 52 is a live internal clutch-spider 54 formed preferably with three suitable undercuts or recesses 55 providing inclined surfaces 56. Disposed in each of the recesses 55 is a clutch-element 57 which is engaged by a plunger 58, Fig. 7, backed by a coil-spring 59, the plunger 58 acting to bias the element 57 toward the narrow end of the recess 55 and wedge the same between the inclined surface 56 and the outer clutch-surface 53 of the cup-member 52. As shown in Figs. 5 and 6, the clutch-spider 54 is mounted on a sleeve 60 journaled on the cross-shaft 19. The spider 54 is oscillated constantly during the operation of the stitch-forming de-

vices by means of an actuating lever 61 secured at one end face-to-face with the spider 54 preferably by means of three screws 62. At its other end the actuating lever 61 is connected by means of a ball-and-socket joint to the lower end of a link 63, Fig. 3, which is connected at its upper end, through a second ball-and-socket joint, to the free end of a vibratory lever 64 pivoted upon a fulcrum-stud 65 and bifurcated to straddle and engage two bearing-blocks 66 embracing a common form of adjustable actuating eccentric 67 fast upon the upper shaft 44. As the upper shaft 44 is rotated the eccentric 67 imparts movement to the lever 64 which, through the link 63, operates the actuating lever 61 connected to the live clutch-spider 54. The live clutch-spider 54, through the clutch-elements 57, drives the bevel gear 20 which rotates the feed-cam 10.

The speed with which the third feeding mechanism rotates the feed-cam is dependent upon the amount of eccentricity of the eccentric 67 and the effective length of the vibratory lever 64 between the eccentric 67 and the vibratory lever fulcrum-stud 65. As shown in Fig. 15 the eccentricity of the eccentric 67 is adapted to be regulated by means of an adjusting screw 68, whereby the vibratory lever 64 may be actuated through a greater or less arc per rotation of the needle-actuating shaft 44. To provide for changing the effective length of the vibratory lever between the eccentric 67 and the vibratory lever fulcrum-stud 65, the latter is formed so that its longitudinal axis is offset to one side of the longitudinal axis of the shank 69, Fig. 15, of the fulcrum-stud which is journaled in a bearing-lug 70 attached to the bracket-arm 3. Pinned to the other end of the fulcrum-stud shank 69 is a control-lever 71 apertured at its free end to receive a detent-plunger 72 fitted at one end with a knurled head 73 and at its other end biased by means of a spring 74, Fig. 16, into one of a plurality of locking apertures 75 provided in an index plate 76 attached to the bearing-lug 70. As disclosed in Fig. 17, the index plate 76 with which the present machine is fitted has but two locking apertures 75, one in the lower portion of the index plate for eye buttonholes and another in the upper portion of the index plate for straight buttonholes. The two locking apertures illustrated are positioned at the extreme limits of adjustment and it is to be understood that any number of apertures may be provided in the index plate between the two apertures shown, and that these additional apertures would represent intermediate positions between the two extreme positions. When the detent 72 is positioned as shown in Figs. 3 and 17, the longitudinal axis of the fulcrum-stud 65 is at a maximum distance from the axis of rotation of the eccentric 67, in which case the amplitude of movement of the point of junction of the vibratory lever 64 and the link 63 for a given amount of eccentricity of the eccentric 67 is at a minimum. When the detent 72 is positioned in the aperture indicated for straight buttonholes the longitudinal axis of the fulcrum-stud 65 is located at a minimum distance from the axis of rotation of the eccentric 67, in which case maximum oscillations are imparted to the clutch-actuating lever 61, thereby to more widely separate the radial stitches about the end of the straight buttonhole.

As previously mentioned the live clutch-spider 54 is continuously operated during the entire period of operation of the stitching mechanism. Automatic means is provided for throwing the clutch

into and out of operation to render the third feeding mechanism effective or ineffective at predetermined periods in the buttonhole cycle. Referring to Figs. 4, 5, 6, and 7, it will be observed that the clutch-spider 54 is undercut, as at 77, adjacent each of the three clutch-elements 57 to provide clearance for clutch-dog-releasing levers 78 each of which has a cylindrical shank 79 journaled in the clutch-spider 54. Preferably pinned to one end of the shank 79 is an arm 80 to which is mounted a roller 81 adapted to engage the periphery of a release-cam 82, Fig. 7, mounted for free rotation on the sleeve 60 carried by the cross-shaft 19. The release-cam 82 is secured, as by screws 83, face-to-face with a plate-member 84 also journaled upon the sleeve 60 and having a pair of radial arms 85, 86. Attached to the outer end of the radial arm 85 is a depending link 87 slotted at its lower end to receive a pin 88 fixed in the free end of a lever 89 pivoted at its lower end to an upstanding ear 90 provided on one end of a transversely shiftable slide 91, Fig. 10, guided by a block 92 and retained against the milled bottom surface of the bed-reinforcing-rib 93 by a pair of plates 94.

Mounted on the lever 89 intermediate its ends is a roller 95 adapted to be engaged by one of a plurality of face-to-face stacked cams 96, 97 fastened, by means of the elongated slot 98 and screw 99 for limited circular adjustment, upon the face of the bevel gear 20, Figs. 7 and 8, and shaped to rest on the periphery of the clutch-member 52 to prevent turning about the screw 99. Cam 97 is secured to cam 96 by the screw 100. It will be understood that as the bevel gear 20 is turned by the bevel gear 21 on the feed-cam 10, which is rotated by the gear-train 40 during the stitching of the buttonhole, the cams 96 and 97 are brought into engagement with the roller 95, thus swinging the lever 89 downwardly about its pivotal axis and, through the link 87, turning the plate-member 84 and the release-cam 82 in a counterclockwise direction as viewed in Fig. 4, against the action of a coil-spring 101 acting between the radial arm 86 and the machine-bed 1. Turning of the release-cam 82 in a counterclockwise direction relative to the rollers 81 on the clutch-dog-releasing levers 78, moves the concentric outer surfaces 102 (Fig. 7) of the release-cam out of range of the rollers 81, thus enabling the plungers 58 and the springs 59 to urge the clutch-elements 57 into wedging relation between the clutch-spider 54 and the cup-member 52. The concentric inner surfaces 103, Fig. 7, of the release-cam 82 are spaced sufficiently near to the axis of the cross-shaft 19 so that the clutch-dog-releasing levers 78 will in no way interfere with the wedging action of the clutch-elements 57. When the clutch-elements are free to act under the action of the springs 59, movements imparted to the lever 61 by the eccentric 67 rotate the bevel gear 20 and hence the feed-cam 10 in step-by-step fashion; the extent or amplitude of these step-by-step movements being governed by the eccentricity of the eccentric 67 and the effective length of the vibratory lever 64. When the step-by-step impulses imparted to the feed-cam 10 exceed those delivered by the slow step-by-step stitching feed, it will be understood from Figs. 18 and 19 that the pawls 48 and the feed-cam 10, to which the pawls are pivotally secured, turn in a counterclockwise direction, Fig. 18, relative to the ring-gear 45; the pawls 48 riding over the ratchet-teeth 50 in a direction not to interfere with the intermittent rotation of the ring-gear

45 which is transmitted to the ring-gear by the gear-train 40 throughout the entire stitching cycle. In other words, since the turning impulses imparted to the feed-cam 10 by the novel third feeding mechanism exceed those imparted to the feed-cam 10 by the slow stitching feed when the clutch of the third feeding mechanism is thrown into effective driving relation with the feed-cam 10, the third feeding mechanism overdrives the slow stitching feed and increases the spacing between successive stitches constituting the buttonhole.

In order that the present invention may be utilized on machines adapted to sew either eyelet or straight buttonholes, the lever 89 is supported upon the transverse slide 91 which is adapted to be shifted endwise a limited extent. This limited shifting of the slide 91 is desirable so that when stitching eyelet buttonholes the roller 95 on the lever 89 can be positioned within the range of movement of the cam 96, or, when stitching straight buttonholes, the roller 95 can be positioned within the range of movement of the cam 97. The active periphery of the cam 96 is of sufficient length to maintain the third feeding mechanism in effective action long enough to properly distribute the radial stitches around the entire eye of the buttonhole. The active periphery of the cam 97 is shorter than that of cam 96 inasmuch as the number of stitches distributed around the end of a straight buttonhole is less than that required for the end of an eyelet buttonhole. To insure the same even distribution of radial stitches on the last half of the eye of the buttonhole as on the first half of the eye the outer surface of the cam-assembly 96, 97 adjacent its trailing end is relieved, as indicated at 104, to position the clutch-dog-releasing levers 78 such that they will effect a slightly earlier release of the clutch-elements, thereby to shorten the effective stroke of the clutch and compensate for the slight overthrow in the feeding mechanism caused by the inertia of the parts and the reduction of friction in the work-clamp shifting cam-mechanism.

The means for shifting the slide 91 so that roller 95 will be properly positioned for engagement either by cam 96 or by cam 97 is best shown in Figs. 10 and 11. Suitably attached to the left hand end-portion of the slide 91 is an upwardly extending lug 105 apertured adjacent its upper end to receive a shift-rod 106 journaled intermediate its ends in the left hand sidewall of the bed 1 and having fixed on its outer end a head 107 by which the shift-rod 106 can be turned about its longitudinal axis and shifted endwise. The rod 106 is mounted to turn freely in the lug 105, but is constrained from moving endwise in the lug 105 by a collar 108 and the hub of an arm 109 of which the free end is connected by a tension-spring 110 to the bed 1. Secured on the shift-rod 106 adjacent the head 107 is a stop-arm 111 which is biased by the tension-spring 110 into cooperation with a selected one of a plurality of stop-notches 112, 113, 114, Fig. 11, formed in an angle-member 115 on the bed 1. The stop-notches are arranged in line, with each suitably labeled as shown in Figs. 10 and 11. When the stop-lever 111 is positioned as shown in full lines 70 in Figs. 10 and 11, i. e., with the stop-arm 111 in the notch 112 labeled "Reg.", the slide 91 is located in its extreme left hand position, in which position the roller 95, Fig. 10, is outside the path of movement of the cam-assembly 96, 97 and is not affected thereby. With this setting the third

feeding mechanism is not thrown into effective action at any time during the buttonholing operation and consequently the sewing machine operates in a manner similar to previous machines and effects the production of a buttonhole such as illustrated in Fig. 12.

When it is desired to produce an eyelet-end buttonhole having fewer stitches in the eye than usual such as shown in Fig. 13, of the drawings, the shift-rod 106 is turned sufficiently to move the stop-arm 111 out of the notch 112, after which the shift-rod 106 is shoved axially to move the roller 95 close to the face of the bevel gear 20, Fig. 2, and into the path of movement of the cam 96. To maintain the roller 95 so positioned, the stop-arm 111, when in register with the stop-notch 114, is released and the tension-spring 110 biases the stop-arm into the notch 114, as shown in dotted lines in Fig. 11. With the roller 95 in the position as shown in Fig. 2, the cam 96, at the proper selected time in the stitching cycle, engages the roller 95 and pivots the lever 89, Fig. 4, about its fulcrum, thereby turning the plate-member 84 through the link 87 to a position such that the cam 82, Fig. 7, frees the clutch-dog-releasing levers 78 to permit the clutch-elements 51 to intermittently couple the constantly operating clutch-spider 54 to the cup-member 52 and hence rotate the feed-cam 10 through the bevel gears 20, 21 at a speed in excess of that imparted to the feed-cam by the usual stitching feed.

When it is desired to produce a straight buttonhole having a plurality of radial stitches produced at one end of the buttonhole, such as in the case of "lapel" buttonholes, Fig. 14a, the shift-rod is positioned so that the end of the stop-arm is located in the stop-notch 113, in which position of the stop-arm the roller 95 is moved into the path of travel of the cam 97. The cam 97 is smaller than cam 96 and hence the period of effective operation of the third feeding mechanism is shorter.

In some cases it is desirable to hand-stitch buttonholes. To facilitate the hand sewing operation, it is advantageous to baste and cut the buttonhole by machine in preparing the same for the hand sewing operation. The present invention provides manually operated means by which a regular machine may be quickly converted into a machine suitable for basting buttonholes. To this end, the plate-member 84, Fig. 9, is formed with a projection 116 to which is fastened an arm 117 overlying a cam-arm 118 attached at one end to a block 119 secured by means of a set-screw 120 on a rod 121 journaled at its opposite ends in the sidewalls of the bed 1. Secured to the exposed left hand end of the rod 121 is an upstanding hand-lever 122 by which the rod 121 is adapted to be turned in its bearings to shift the plate-member 84, together with the cam 82, from the position shown in Fig. 4 to the position shown in Fig. 9, in which latter position the clutch-dog-release levers 78 are freed, thus enabling the clutch-elements 51 to effectively couple the clutch-spider 54 to the cup-member 52 and drive the feed-cam 10. It will be understood that as long as the hand-lever 122 remains in the dot-and-dash position shown in Fig. 9, the third feeding mechanism is effective and over-drives the slower stitching feed to rotate the feed-cam 10 at a speed such that the stitches constituting the buttonhole are distributed as shown in Fig. 14. After the basting and buttonhole-cutting operations are completed, the buttonhole is finished in

a subsequent hand sewing operation. Obviously, the hand-lever 122 may be operated anytime during the stitching cycle without affecting the relative timing between the various mechanisms in the machine.

From the above description it will be understood that the present invention contemplates an automatic mechanism to be incorporated in buttonhole sewing machines adapting the machines for producing buttonholes having the stitches around an end of the buttonhole spaced a greater distance apart than along each side thereof. Also, the present invention contemplates a manual control for the above described mechanism by which the same may be rendered effective for any portion of the stitching cycle or for the entire stitching cycle. Further, the novel feeding mechanism is constructed so that, if desired, the step-by-step gear-feed can be rendered inoperative by swinging one of the gears 40 out of meshing relation with its adjacent gear, and the novel feeding mechanism substituted for the gear-feed. When this is done a variation in the total number of stitches constituting the buttonhole can be readily obtained by adjusting the eccentricity of the eccentric 64, the effect of which eccentricity can be augmented by varying the effective length of the lever 64.

Having thus set forth the nature of the invention what we claim herein is:

1. In a sewing machine of the buttonhole type, in combination, stitch-forming mechanism, a work-holder, and means to effect relative movements between said work-holder and stitch-forming mechanism to space the stitches about the buttonhole, said means including a first feeding mechanism to relatively move the stitch-forming mechanism and work-holder progressively in sewing a portion of the buttonhole, a second step-by-step feeding mechanism operable to overfeed said first feeding mechanism to relatively move the stitch-forming mechanism and the work-holder progressively in sewing about another portion of the buttonhole, automatic means for throwing said second feeding mechanism into and out of effective operation, and means for selectively changing the period of duration of the effective action of said second feeding mechanism.
2. In a sewing machine of the buttonhole type, in combination, stitch-forming mechanism, a work-holder, and means to effect relative movements between said work-holder and stitch-forming mechanism to space the stitches about the buttonhole, said means including a first feeding mechanism to relatively move the stitch-forming mechanism and work-holder progressively in sewing a portion of the buttonhole, a second feeding mechanism to relatively move the stitch-forming mechanism and the work-holder progressively in sewing about another portion of the buttonhole, a plurality of cams, means controlled by a selected one of said cams for throwing said second feeding mechanism into and out of effective operation, and manually shiftable means for rendering any one of said cams effective.
3. In a sewing machine of the buttonhole type, in combination, stitch-forming mechanism, a work-holder, and means to effect relative movements between said work-holder and stitch-forming mechanism to space the stitches about the buttonhole, said means including a pair of constantly actuated separate feeding mechanisms successively rendered effective for producing a

progressive relative movement between said stitch-forming mechanism and work-holder during the formation of the stitches along the side portions and around one end-portion of the buttonhole, and automatic means for rendering one of said feeding mechanisms effective to overfeed the other of said feeding mechanisms during a portion of the cycle of stitches made around the buttonhole.

4. In a buttonhole sewing machine, the combination with stitch-forming mechanism and a work-holder which are relatively movable to space the stitches about a buttonhole of a first feeding mechanism to relatively move the stitch-forming mechanism and work-holder progressively in sewing a portion of the buttonhole, a second feeding mechanism to relatively move the stitch-forming mechanism and work-holder progressively in sewing another portion of the buttonhole, said second feeding mechanism including a step-by-step driving element constantly actuated during the entire stitching cycle, and automatic means operable to render effective said constantly actuated element to drive said second feeding mechanism for a predetermined portion of the stitching cycle.

5. In a sewing machine of the buttonhole type, the combination with stitch-forming mechanism and a work-holder which are relatively movable to space the stitches about a buttonhole, a feed-cam for effecting a relative movement between said stitch-forming mechanism and said work-holder, a transverse rotary shaft, and means connecting said rotary shaft with said feed-cam, of means for imparting a continuous rotary motion to said transverse shaft for a portion of the buttonholing cycle to drive said feed-cam, and means for imparting an intermittent rotary motion to said transverse shaft for another portion of the buttonholing cycle also to drive said feed-cam.

6. A sewing machine having stitch-forming mechanism and a work-holder which are relatively movable to space the stitches, a rotary shaft, and feeding means for effecting progressive relative movement between the stitch-forming mechanism and the work-holder, said feeding means including an intermittent driving element, a vibratory lever actuated by said rotary shaft, means connecting said vibratory lever with said intermittent driving element, and a fulcrum-stud providing an eccentrically located pivot for said vibratory lever, said fulcrum-stud being mounted for turning movement thereby to shift the pivot of said vibratory lever to change the effective length of the same.

7. A sewing machine having stitch-forming mechanism and a work-holder which are relatively movable to space the stitches, a rotary shaft, an adjustable eccentric carried by said rotary shaft, and feeding means for effecting progressive relative movement between the stitch-forming mechanism and the work-holder, said feeding means including a driving clutch-element, a vibratory lever pivotally supported and embracing said adjustable eccentric, means connecting said vibratory lever with said driving clutch-element, and a fulcrum-stud having a portion providing an eccentrically located pivot for said vibratory lever, said fulcrum-stud being mounted for circular adjustment to provide for changing the effective length of said vibratory lever to augment the range of adjustment afforded by the adjustable eccentric.

8. Work-feeding mechanism for sewing ma-

chines comprising, a work-clamping member, a rotary shaft, an actuator carried by said shaft, a vibratory lever having a follower portion embracing said actuator, a shiftable fulcrum for said lever for varying its amplitude of vibration, and means to transmit work-feeding movement of said lever to said work-clamping member.

9. Work-feeding mechanism for sewing machines, comprising, a work-clamping member, a rotary shaft, an actuator carried by said shaft, a vibratory lever pivotally supported at one end and bifurcated at its other end to embrace said actuator, a shiftable fulcrum supporting said vibratory lever for varying its amplitude of vibration, and means to transmit work-feeding movement of said lever to said work-clamping member.

10. In a sewing machine of the buttonhole type, the combination with stitch-forming mechanism and a work-holder which are relatively movable to space the stitches about a buttonhole, of a first feeding mechanism to relatively move the stitch-forming mechanism and work-holder progressively in sewing about a portion of the buttonhole, a second feeding mechanism to relatively move the stitch-forming mechanism and work-holder progressively in sewing about another portion of the buttonhole, and manually controlled means for rendering said second feeding mechanism effective during the whole or any portion of the cycle of stitches made around the buttonhole.

11. In a sewing machine of the buttonhole type, the combination with stitch-forming mechanism and a work-holder which are relatively movable to space the stitches about a buttonhole, of a first feeding mechanism to relatively move the stitch-forming mechanism and work-holder progressively in sewing about a portion of the buttonhole, a second feeding mechanism to relatively move the stitch-forming mechanism and work-holder progressively in sewing about another portion of the buttonhole, said second feeding mechanism including a driving clutch element, and manually controlled means for rendering said clutch element effective during the whole or any portion of the cycle of stitches made around the buttonhole to drive said second feeding mechanism.

12. In a buttonhole sewing machine, the combination with stitch-forming mechanism and work-holding means movable relative to each other to sew around a buttonhole, of a plurality of separate feeding mechanisms successively rendered effective for producing a progressive relative shift between said stitch-forming mechanism and said work-holding means during the formation of the stitches around the buttonhole, and means for selectively changing the period of duration of the effective action of one of said feeding mechanisms.

13. In a buttonhole sewing machine, the combination with stitch-forming mechanism and work-holding means movable relative to each other to sew around a buttonhole, of a plurality of separate feeding mechanisms successively rendered effective for producing a progressive relative shift between said stitch-forming mechanism and said work-holding means during the formation of the stitches around the buttonhole, an intermittent clutch included in one of said feeding mechanisms, a plurality of cams, means controlled by a selected one of said cams for rendering said intermittent clutch effective, and

manually shiftable means for rendering any one of said cams effective.

14. In a sewing machine of the buttonhole type, in combination, stitch-forming mechanism and a work-holder which are relatively movable to space the stitches about a buttonhole, a feed-cam for effecting a relative movement between said stitch-forming mechanism and said work-holder, means including an intermittent driving member for rotating said feed-cam, means operable to render said driving member effective, and means for selectively changing the period of duration of the effective action of said driving member.

15. In a sewing machine of the buttonhole type, in combination, stitch-forming mechanism and a work-holder which are relatively movable to space the stitches about a buttonhole, a feed-cam for effecting a relative movement between said stitch-forming mechanism and said work-holder, means including an intermittent driving member for rotating said feed-cam, a plurality of cams, means controlled by a selected one of said cams for rendering said intermittent driving member effective, said last named means including a lever provided with a roller, and means for shifting said roller into cooperative relation with a selected one of said cams.

16. In a sewing machine of the buttonhole type, in combination, stitch-forming mechanism and a work-holder which are relatively movable to space the stitches about a buttonhole, a feed-cam for effecting a relative movement between said stitch-forming mechanism and said work-holder, means including a one-way acting clutch for rotating said feed-cam, said clutch having an outer clutch surface, an inner clutch surface, and a plurality of clutch-elements interposed

between said outer and inner clutch surfaces, a clutch-element-releasing lever for each of said clutch-elements, a release-cam normally maintaining said clutch-element-releasing levers in 5 positions such that the clutch-elements are held out of wedging position between said inner and outer clutch surfaces, a plurality of cams, a lever cooperating with a selected one of said cams for shifting said release-cam out of engagement 10 with said clutch-element-releasing levers so that said clutch-elements can move into wedging position, and means for shifting said lever into cooperative relation with a selected one of said cams.

15 17. In a sewing machine of the buttonhole type, in combination, stitch-forming mechanism and a work-holder which are relatively movable to space the stitches about a buttonhole, a feed-cam for effecting a relative movement between 20 said stitch-forming mechanism and said work-holder, means including a one-way acting clutch for rotating said feed-cam, said clutch having an outer clutch surface an inner clutch surface, and a plurality of clutch-elements interposed between 25 said outer and inner clutch surfaces, a clutch-element-releasing lever for each of said clutch-elements, a release-cam spring-biased into a position to normally maintain said clutch-element-releasing levers in positions such that the clutch- 30 elements are held out of wedging position between said inner and outer clutch surfaces, and manually controlled means operable at will for shifting said release-cam to a position out of engagement with said clutch-element-releasing 35 levers so that said clutch-elements can move into wedging position.
